UNITED STATES PATENT OFFICE.

HENRY S. LOCKWOOD, OF SOUTH NORWALK, CONNECTICUT, ASSIGNOR TO
THE LOCKWOOD MANUFACTURING COMPANY, OF SAME PLACE.

DESIGN FOR A TOY PISTOL.

SPECIFICATION forming part of Design No. 13,471, dated December 5, 1882.

Application filed November 2, 1882. Term of patent 7 years.

To all whom it may concern:

Be it known that I, HENRY S. LOCKWOOD, of South Norwalk, in the county of Fairfield and State of Connecticut, have invented and produced a new and original Design for Toy Pistols, of which the following is a specification, reference being had to the accompanying drawing, forming part thereof.

In the drawing my new design is illustrated by a side view of the pistol.

The leading feature of my design is the hammer A, at the rear of the barrel, made in form of an elephant, its fore feet being above the cap-receptacle a. B is the barrel, and C the handle.

This design adds largely to the ornamental

appearance of the pistol, and the elephant, being hinged, it can be made to assume two positions—one erect on its hind legs and the other standing on four legs.

I claim—

1. The hereinbefore-described design for toy pistols, which consists in a hammer in form of an elephant placed in relation to the barrel and handle, as specified.

2. The hereinbefore-described design for pistols, which consists of barrel B, handle C, and hammer A, made in form of an elephant.

HENRY S. LOCKWOOD.

Witnesses:
